UNITED STATES PATENT OFFICE.

JAMES N. RICE, OF CHICAGO, AND JOSEPH HUMPHREYS, OF AUSTIN, ILL.

COMBINATION-LOCK.

SPECIFICATION forming part of Letters Patent No. 292,253, dated January 2, 1884.

Application filed September 6, 1882. (Model.)

To all whom it may concern:

Be it known that we, JAMES N. RICE and JOSEPH HUMPHREYS, respectively of Chicago and Austin, Cook county, Illinois, have invented a Combination Lock or Locks, to be applied to doors, drawers, sashes, gates, &c., of which the following is a specification.

Our invention relates to that class of locks which are applied to drawers, doors, lids, and window-sashes; and the nature of it consists in combinations and constructions, all as will hereinafter be described and claimed, reference being had to the accompanying drawings, in which—

15 Figure 1 is a front elevation; Fig. 2, a vertical section, showing the bolt drawn back so that the bit is in the slot of the tumblers; Fig. 3, a similar view, with bit in the slot of the locking-plate, so that the tumblers can be 20 revolved; Figs. 4, 5, and 6, perspectives of the three tumblers; Fig. 7, a perspective of the catch, the plate to which it is attached, and the bolt for operating it; Fig. 8, a rear elevation of the shell B, lugs b³, and locking-plate D.

A represents a part of a door, drawer, window-sash, or similar structure; B, the body or shell of the lock, having a notch b²; C, the bolt, having bit c; D, the locking-plate, having slot d; E E' E², the tumblers; F, the dial; G, the set-screw; H, the catch; I, studded plate for holding the catch; K, the inclosing-plate, which, with the plate I, forms a recess for the catch to move in.

35 The shell B is attached to the drawer by straps b, which have inside screw-threaded lugs b³ for bolts passed through the part A, so that when used upon a drawer or door nothing will be exposed that will permit the shell to be 40 removed. Within the shell are three tumblers, E E' E². The tumbler E² has a screw-threaded extension, e², which passes through the shell, and is provided with a nut or set-screw, G, which clamps the dial F against the shell. It is also provided with a rear extension, e³, having a slot, e⁴. Upon its periphery is a pin, e⁵, which, when the tumbler is 45 revolved, strikes a pin, e', on tumbler E', which turns in the same direction, and has its bearings on extension e³. This tumbler has also an extension, e⁶, to serve as a bearing for tumbler, E. A slot, e⁷, is also formed in extension e⁶,

which is provided with a pin, e¹⁰. This pin, when tumbler E is revolved, strikes a pin, e⁸, on tumbler E, which is also provided with a 55 slot, e⁹.

Passing through the nut G, tumbler E², part A, and plates D, I, and K is a bolt or key, C, having a pin, c, which, when the slots e⁴ e⁷ e⁹ register, can be drawn in the shell to prevent 60 the slots from losing their register and permit the bolt to be rocked. When pushed into the slot d, the bolt cannot be turned, and if the tumblers are disarranged by turning screw or nut G it cannot be drawn back until the slots 65 are again made to register. The end of the bolt is scarfed at c' to form a rigid seat for the catch H, which is provided with an aperture, h, of a shape similar to a cross-section of the scarfed part of the bolt. The catch H is provided with a flared slot, h', which embraces a pin, i, on plate I. This pin serves as a stop when the catch is in position shown in full lines, Fig. 7, and a second pin, i', serves as a stop for catch when turned as shown in dotted line, Fig. 7.

70 The operation is as follows: The dial is set so that one figure or a fraction of a figure registers with the notch b², and the slot e⁴ made to register with the figure. The slots are made 75 to register, as shown in Fig. 2, and the bit c drawn into them. The catch H can now be rocked. By pushing the bolt or key in, as shown in Fig. 3, the catch is held immovably. If the screw G be turned, the register of the 80 slots is destroyed, and the bit can only be drawn back by turning the dial to the combination of figures which make the slots register with the slot in the locking-plate. The 85 combination is used in the same way as the ordinary combination-lock, and further description is unnecessary.

It is obvious that this device, if used upon a window-sash, will prevent a burglar from lifting the latter, even if the window is broken, 90 as he could not see how to operate the dial. If placed upon a drawer, the shell will serve as a handle for operating the drawer.

What we claim as new is—

1. In a lock, the combination of a shell having means for attaching it to a door or other object, tumblers within said shell, having slots and pins which strike each other when the tumblers are turned, a locking-plate to be at-

tached to the object, and having a slot, d , a bolt having a bit which may be forced into the slot d or drawn into the slot formed by the tumblers, a set-screw for turning the tumblers, 5 and a catch upon the opposite end of the bolt, and adapted to be turned with the latter, substantially as described.

2. In a lock, the combination of a shell having means for attaching it to an object, and 10 having a movable dial on its face, tumblers within said case having pins and slots, and one having a screw-threaded extension, which extends outside of the shell, a nut or screw on said extension for clamping the dial in place 15 and turning the tumblers by means of the screw-threaded tumbler, a locking-plate to be attached to the object, and having a bit-slot, a bolt passing through the tumblers, and having a bit which may be drawn in the tumblers' 20 slots or forced into the slot in the locking-plate, and a catch upon the opposite end of the bolt, and adapted to be turned when the bit is in the tumblers' slots, substantially as described.
- 25 3. In a lock, the combination of a shell having means for attaching it to an object, a bolt passing through the shell and having a bit and catch, a series of tumblers, one journaled in

the bolt, and having a screw-threaded extension at one end, a slot at the other, and an intermediate pin, and the others journaled upon an extension of the first tumbler, and having slots at one end adapted to register with the slot in the first tumbler, and pins attached to and between the tumblers, and a screw, G , for 30 revolving the thimbles, substantially as described.

4. In a combination-lock, the combination of a tumbler having a screw-threaded extension, e^2 , an extension, e^3 , a slot, e^4 , and a pin, 40 e^5 , a second tumbler journaled upon the extension e^3 , and having a slot, e^6 , and pins e^7 and e^8 , a third tumbler journaled upon extension e^6 , and having pin e^9 and slot e^{10} , a screw-nut, G , upon extension e^2 , a bolt, C , having a bit, 45 e , which may be drawn into the slots when the latter are made to register, and a catch which may be turned when the bit is in said slots, substantially as and for the purpose set forth.
